UNITED STATES PATENT OFFICE.

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Application filed December 29, 1919, Serial No. 348,065. Renewed July 30, 1925.

To all whom it may concern:

Be it known that I, ALFRED B. FOWLER, a citizen of the United States, residing at Beverly, in the county of Essex and State of

5 Massachusetts, have invented certain new and useful Improvements in Sewing Machines; and I do hereby declare the following to be a full, clear, and exact description of the invention, such as will enable others 10 skilled in the art to which it appertains to make and use the same.

This invention relates to sewing machines and more particularly to curved hook needle sewing machines employed for sewing together 15 the soles and uppers of shoes. The present embodiment of the invention is designed especially to sew together the soles and uppers of turned shoes although, with slight changes, it may be employed for sewing 20 the inseams of welted shoes.

Shoe sewing machines of this class are commonly provided with an awl or feed point that engages the between substance of the shoe sole inside of the channel and at 25 one side of the channel guide. With such relative arrangement of the feed point and channel guide, considerable difficulty has been experienced in sewing about the toe of a pointed toe shoe. Accordingly, it has been 30 proposed to arrange the feed point so that it will engage the top of the between substance, thereby permitting the feed point to be operated across the end of the channel guide. As heretofore operated, however, 35 the pressure of the feed point on the shoe is maintained after the needle is retracted and the work holding devices of the machine are released which is objectionable, as it has been found that the pressure of the feed 40 point on the work at this time tends to force the shoe downwardly out of proper position relatively to the needle. Moreover, the feed point has heretofore been arranged to engage the center of the between substance 45 with the result that it is liable to strike the lasting tacks and to injure the between substance materially which, of course, is also objectionable.

One of the objects of the present invention 50 is to provide an inseam shoe sewing machine in which the feed point, although engaging the top of the between substance, is

arranged and actuated in such manner as to overcome the disadvantages of both of the prior constructions above described while 55 retaining all of the advantages.

With this and other objects in view, a feature of the present invention contemplates the provision in a sewing machine of a feed point actuating mechanism acting to force 60 the feed point into the work, then to relieve the pressure of the feed point on the work and then while the pressure of the feed point on the work is relieved to actuate the feed point to feed the work. This feature of the 65 invention is particularly applicable to an inseam shoe sewing machine in which the feed point is arranged to engage the shoe at the top of the between substance of the sole, as the relieving of the pressure of the feed 70 point overcomes any tendency of the work being forced downwardly by the feed point when the needle is retracted and the work holding devices of the machine are released.

In connection with this feed point a channel guide is preferably employed that is maintained stationary in the direction of feed in close proximity to the root of the channel during the feeding operation. Preferably the feed point engages the between substance in the plane of the root of the channel or in the line of connection of the channel flap and between substance so that the body of the between substance will not be weakened or mutilated by the feed 75 point and there is no danger of the feed point striking a lasting tack. Also this arrangement of the feed point brings it as close as possible to the channel guide and thereby permits the sharp turning movement 80 necessary in sewing around the toe of a narrow toed shoe. In the preferred embodiment of the invention the channel guide has no movement longitudinally of the channel during the operation of the machine but is 85 movable transversely of the channel. Preferably, however, the transverse movement of the channel guide is only sufficient to relieve the pressure thereof on the work during the feeding operation so that the work may be 90 freely fed and so as to obviate any danger of the feed point striking the channel guide, while during the work piercing and loop drawing strokes of the needle the channel 95

guide cooperates with other work holding devices of the machine to hold the work firmly.

Another object of the present invention 5 is to ensure, in an inseam shoe sewing machine provided with thread severing and holding devices, that the first stitch will be formed during the first cycle of operations of the machine.

10 With this object in view, a feature of the invention contemplates the provision in a sewing machine having a thread finger, a looper, and means acting automatically upon stopping the machine to sever and hold the 15 thread, of actuating mechanism for the thread finger acting to position the thread finger so that when the machine is again started the thread finger will at once properly engage the thread and effectively assist 20 in the formation of a stitch during the first cycle of operations of the machine. In the preferred embodiment of the invention the thread engaging end of the thread finger is curved upwardly and when the machine is 25 stopped is positioned close to the stretch of thread leading from the looper to the thread severing and holding mechanism.

Other features of the invention comprise 30 certain constructions, arrangements and combinations of parts hereinafter described and claimed the advantages of which will be obvious to those skilled in the art.

The several features of the invention will 35 be clearly understood from the following description and accompanying drawings in which:

Figure 1 is a front elevation of a portion of the head of an inseam shoe sewing machine embodying the features of the invention 40 in their preferred form; Fig. 2 is a sectional plan view partly diagrammatical showing the relative arrangement of the needle, looper, thread finger and thread cutting and holding device when the machine 45 is in stopping position; Fig. 3 is a right side elevation, partly in section and with parts broken away, of the portion of the machine illustrated in Fig. 1; Fig. 4 is an enlarged sectional plan view of the portion 50 of the machine illustrated in Fig. 1; Fig. 5 is a front elevation, partly broken away, of a portion of the head of the machine; and Figs. 6 and 7 are sectional views taken on the line 6—6 of Fig. 5, showing respectively 55 the relative arrangement of the feed point, channel guide and needle immediately after the feed point engages the work, and the relative arrangement of these parts after the feed point has left the work at the completion of the feeding operation.

The machine as illustrated in the drawings is provided with a curved hook needle 2, a thread finger 4, a looper 6, a thread truck 8, a back gage 10, a back rest or bunter 12 and 65 a thread severing and holding device 14, all

of which parts have the same general arrangement and mode of operation, except as hereinafter described, as the corresponding parts of the machine illustrated and described in applicant's copending application 70 Serial No. 298,589, filed May 21, 1919.

The needle 2 is secured in the usual manner to a pivotally mounted needle segment 16 which is connected by a link 18 to a cam actuated lever 20.

75 The thread severing and holding device of the machine is timed to operate so as to cut off the thread during the last cycle of operations of the stitch forming devices of the machine and to hold the end of the thread 80 leading to the supply until the machine is again set into operation. When the machine is again set into operation, the thread severing and gripping jaws of the device are at once advanced to give up thread to the 85 thread finger. The thread is held by the thread gripping jaws during the formation of the first stitch and during the first work piercing stroke of the needle. The mechanism for thus actuating the thread severing 90 and holding device may be and preferably is the same as illustrated and described in said co-pending application, which mechanism is thrown into operation by the raising 95 of a control rod 21.

In the illustrated machine the thread finger 4 is of such shape and is so positioned relatively to the thread being held by the thread severing and holding device when the machine is stopped as to insure that the thread finger will properly engage the thread at the start of the next cycle of operations of the machine. With this in view, the extreme end of the thread finger is curved upwardly as illustrated in the drawings and is positioned close to the thread leading from the looper to the thread gripping jaws when the machine is stopped so that upon starting the machine the end of the thread finger will at once properly engage the thread to assist in forming a stitch during the first cycle of operations. The thread finger is secured to the lower end of a vertical shaft 22, the upper end of which shaft is secured to a gear 24 that meshes with rack teeth 26 100 formed on the forward end of a horizontally sliding bar 28. The bar 28 is actuated to impart the desired movement to the thread finger by means of a roll 30 on the rear end of the bar which engages a cam groove 32 105 in an oscillating lever 34. The lever 34 is pivoted at 36 on the frame of the machine and is connected by a link 38 with the cam actuated lever 20.

110 The back rest or bunter 12 is mounted upon a forwardly spring pressed slide 40. The back gage 10 is formed on the forward end of a back gage carrier 44 which is connected by a link 46 with the back gage locking slide 42, one end of the link being piv- 115

oted upon a stud 48 secured to the carrier 44 and its other end being pivoted on a stud secured to the slide 42. The back gage carrier is guided by means of a pin 50 secured 5 to the frame of the machine which extends through a horizontal slot in the carrier. The free end of an arm 52 is also pivoted upon the stud 48, which arm is secured to a rock shaft 54. An arm 56 is pivoted upon 10 the rock shaft 54 and is connected to the arm 52 by a torsion spring 58 which is relatively under no tension. During the work piercing stroke of the needle the back gage is caused to engage the work lightly and is 15 then pressed against the work under increasing pressure by means of a stud 60 on the needle actuating link 18 which engages the arm 56 and through the torsion spring 58 and arm 52 thus actuates the back gage. 20 The back gage and back rest are locked in engagement with the work at the limit of this stroke of the needle and until the needle returns to the limit of its loop drawing stroke. The mechanism above described 25 for actuating the back gage and back rest may be and preferably is the same as illustrated and described in said co-pending application.

In order that the back gage may not interfere with the feeding of the work, means 30 are provided for retracting the back gage after the needle has reached the limit of its loop drawing movement. This is accomplished in the machine illustrated in the 35 drawings by means of a coil spring 62 arranged to act in the direction of the movement of the back gage, having one end secured to the stud which forms the pivotal connection between the link 46 and the locking slide 42 and its other end secured to the 40 frame of the machine. When the back gage is unlocked at the limit of the loop drawing stroke of the needle, the spring 62 will act to retract the back gage. As the torsion 45 spring 58 is under no tension at this time, it will not interfere with this action of the coil spring 62, and also as the strength of the coil spring is considerably less than that of the torsion spring 58, the coil spring will 50 not interfere with the action of the torsion spring in advancing the back gage during the work piercing stroke of the needle.

The illustrated machine is provided with 55 a channel guide 64 which is immovable longitudinally of the channel and, except when the work is being fed, firmly engages the root of the channel to cooperate with the back gage and bunter in holding the work. During the feeding of the work, the channel 60 guide is retracted slightly to ensure that the feed point hereinafter described will clear the channel guide and to relieve the pressure of the channel guide on the root of the channel but is still maintained in close proximity 65 to the root of the channel in order to guide

the work effectively. The channel guide is thus actuated by means of a cam and spring actuated lever 66-68 to one arm 66 of which the channel guide is secured. The lever 66-68 is pivotally mounted upon a horizontal shaft or rod 70 secured to the frame of the machine and is held from movement longitudinally of the rod by means of collars 72 on the rod engaging the ends of the hub 74 of the lever. The lever 66-68 is actuated 70 through a cam roll 76 mounted on the arm 68 of the lever which engages a cam surface on a cam disk 78 carried by the main shaft 80 of the machine. The cam roll is maintained in contact with the cam surface by a spring connected to the rear end of the lever as illustrated in Fig. 3. In order that the channel guide may act effectively on different styles and sizes of shoes, the channel 75 guide has provision for vertical, transverse and longitudinal adjustments relatively to the channel of the shoe sole. In order to provide for vertical adjustment of the channel guide, the shank of the guide is adjustably secured in a vertical clamp 82 formed 80 in the end of the arm 66. In order to adjust the channel guide transversely of the channel, the arm 66 is adjustably connected with the arm 68 of the cam lever. To this end a split collar 86 is formed on the upper 85 end of the arm 68, which collar embraces the hub 74 formed on the arm 68 and is capable of being rotated on the hub 74 to adjust the channel guide transversely, and is capable of being moved longitudinally of 90 the hub to adjust the channel guide longitudinally of the channel, the arm 66 being held in adjusted position by means of a clamping screw 88 engaging ears formed on the 95 ends of the split collar 86.

The illustrated machine is provided with a feed point 90 which engages the top of the 100 between substance of the shoe sole directly above the root of the channel and has its path of movement across the end of the 105 channel guide. With this arrangement of the feed point it will be seen that the work may be turned about the feed point as desired without interference from the channel guide during the feeding operation so that 110 the toe of the most extremely pointed toe shoe may be properly fed and sewed by the machine without difficulty, the channel guide having a relatively small end that engages the root of the channel as hereinbefore described. The feed point is forced into the work while the work is being held by the needle, the channel guide, the back gage and bunter, and in order that the feed point may not tend to force the work downwardly 115 when the needle is disengaged from the work and during the feeding operation, there is provision for relieving the pressure of the feed point on the work before the needle leaves the work. At the end of the feeding 120

operation the feed point is raised above the work and is then returned into position to again engage the work. The feed point is secured to an arm 92 which in turn is secured to a rock shaft 94 mounted in a bearing in the lower end of a vertical hanger 96. In order to adjust the feed point transversely of the between substance, the feed point is adjustable longitudinally of the 5 arm 92, and in order to adjust the vertical position of the feed point, the arm 92 is rotatably adjustable on the rock shaft 94. The feed point is actuated to feed the work by means of a slide 98 on which the hanger 10 96 is formed. The slide 98 is mounted on the shaft 70 and is actuated by means of a cam actuated lever 100—102 fulcrumed on a vertical stud 104. A cam roll 106 is mounted on the end of the arm 102 of the lever which 15 engages a cam groove in the periphery of the cam disk 78. The lever 100—102 is connected to the slide 98 through a sliding block 107 pivotally connected to the arm 100 of the lever which engages a horizontal groove 20 108 in the upper end of the slide 98. In order to vary the length of the feeding movement of the feed point, the block 107 is adjustable longitudinally of the arm 100. To this end the block is connected to the arm 25 100 by means of a stud 109 engaging a pivot socket in the block 107 which stud is provided with a shoulder 111 engaging the under side of the arm 100 and extends through an elongated slot 110 in the end of the arm. 30 The stud 109 is held in adjusted position in the slot by means of a nut 112 threaded upon the upper end thereof. The slide 98 is held from rotary movement on the shaft 70 by means of a horizontal lug 114 projecting from the upper portion of the slide which lug is in sliding engagement with a pair of lugs projecting from the hub of the 35 lever 100—102.

The feed point is actuated to engage the 40 work, then to relieve the pressure thereof on the work, and at the end of the feeding movement is raised above the work, by the actuation of the rock shaft 94 which in turn is actuated by a cam lever 116. The rock 45 shaft is connected to the cam lever 116 through an arm 118 secured to the right-hand end of the rock shaft, the free end of which arm is slotted or bifurcated to engage a pin 120 projecting laterally from the forward end of a cam lever 116. The pin 120 is elongated to permit the arm 118 to move with the feed slide 98. The cam lever 116 is fulcrumed at 122 on the frame of the machine and its rear end carries a cam roll 50 which engages a cam groove 124 in a side of the cam disk 78. In Figure 3 the cam roll is shown in one of the positions in the cam groove 124 which it assumes during the feeding of the work. At the end of the feeding 55 movement of the feed point, the cam roll 60 which engages a cam groove 124 in a side of the cam disk 78. In Figure 3 the cam roll is shown in one of the positions in the cam groove 124 which it assumes during the feeding of the work. At the end of the feeding movement of the feed point, the cam roll 65

is engaged by the rise 126 in the cam groove 124 which raises the feed point above the work; after the feed point is retracted by the feed slide 98, it is again forced into the work by a depression 128 in the cam groove; 70 and before the start of the feeding operation the pressure of the feed point on the work is relieved and maintained relieved during the feeding operation by the outer wall of the cam groove being backed off and, as illustrated, the inner wall of the cam groove is provided with a slight rise 130 to retract the feed point slightly at this time.

The illustrated machine is provided with mechanism for stopping the machine with 80 the main shaft in a predetermined angular position. Such stop mechanism, however, is not illustrated in the accompanying drawings as it may be and preferably is the same as illustrated and described in said pending 85 application to which reference may be had for a full and complete description of the same.

When the machine is stopped it is desirable that the feed point shall be raised out 90 of engagement with the work. To this end means is provided for swinging the bifurcated arm 118 downwardly which through the rock shaft 94 raises the feed point. In order that the cam actuated lever 116 may not 95 interfere with such movement of the arm 118, the outer wall of the cam groove 124 is cut away at 132 which cut away portion, when the machine is stopped in a predetermined position as above described, is located adjacent the cam roll on the lever 116. The means for thus actuating the bifurcated arm 118 to raise the feed point is actuated by the control rod 21 hereinbefore referred to in connection with the thread 100 cutting and holding device. The connection between the arm 118 and the control rod comprises a rearwardly curved vertical rod 134, the upper end of which is bent at right angles to engage an aperture in a lug 136 110 secured to the elongated pin 120 engaging the arm 118. The lower end of the curved rod 134 extends through an aperture in one end of a lever 138 fulcrumed on the frame of the machine. The upper side of the end of the lever 138 is engaged by a nut and washer 140 secured to the rod, and interposed between the under side of the end of the lever and a nut and washer threaded on the end of the rod is a spring 142 coiled about the rod. 120 The other end of the lever is pivotally connected to the control rod 21. When the control rod 21 is raised upon stopping the machine to throw into operation the thread cutting and holding device, the lever 138 acts 125 through the spring 142 and curved rod 134 to swing the arm 118 downwardly. When the control rod 21 is lowered upon starting the machine, the lever 138 raises the curved rod 134 to its initial position. The aperture 130

in the lug 136 is sufficiently large so that during the normal operation of the machine the curved rod 134 will not interfere with the actuation of the feed point by means of 5 the cam lever 116.

The nature and scope of the present invention having been indicated, and a machine embodying the several features of the invention in their preferred form having 10 been specifically described, what is claimed is:—

1. An inseam shoe sewing machine having, in combination, stitch forming devices, a feed point arranged to engage the shoe at 15 the top of the between substance of the sole, and means to force the feed point into the work, to relieve the pressure of the feed point on the work, and to actuate the feed point to feed the work while the pressure 20 thereof is relieved.

2. An inseam shoe sewing machine having, in combination, stitch forming devices, a feed point arranged to engage the shoe at 25 the top of the between substance of the sole, and means to force the feed point into the work, to move relatively the feed point and work to relieve the pressure of the feed point on the work, and to actuate the feed point to feed the work while the pressure 30 thereof is relieved.

3. An inseam shoe sewing machine having, in combination, stitch forming devices, a feed point, and means to force the feed point into the work, to move relatively the 35 work and feed point to relieve the pressure of the feed point on the work, and to actuate the feed point to feed the work while the pressure thereof is relieved.

4. A sewing machine having, in combination, 40 stitch forming devices, a feed point, and means to force the feed point into the work, to withdraw the feed point slightly to relieve the pressure thereof on the work, and to actuate the feed point to feed the work 45 while the pressure thereof is relieved.

5. An inseam shoe sewing machine having, in combination, stitch forming devices, a feed point acting on the top of the between 50 substance of the sole of the shoe substantially in the plane of the root of the channel, actuating mechanism for the feed point, a channel guide, means cooperating with the channel guide to hold the work, and means to retract the channel guide slightly preliminary to the feeding operation.

6. An inseam shoe sewing machine having, in combination, stitch forming devices, a slide, a feed point acting on the shoe at 55 the top of the between substance of the sole pivotally mounted on the slide, and means for moving the feed point about its pivot to force the feed point into the work to relieve the pressure of the feed point on the work and to actuate said slide to feed the

work while the pressure of the feed point 65 on the work is relieved.

7. An inseam shoe sewing machine having, in combination, devices for guiding a lasted shoe, stitch forming devices including a curved hook needle, a feed point, actuating mechanism for the feed point comprising a cam actuated lever, a control rod, and connections between said rod and cam actuated lever to disengage the feed point from the work upon movement of said rod in 75 one direction.

8. An inseam shoe sewing machine having, in combination, stitch forming devices, a feed point, actuating mechanism for the feed point to force the feed point into the 80 work, to relieve the pressure of the feed point on the work and to actuate the feed point to feed the work, and means connected with members of said actuating mechanism for the feed point to disengage the feed 85 point from the work upon stopping the machine.

9. An inseam shoe sewing machine having, in combination, stitch forming devices, a slide, a feed point, a holder for the feed 90 point comprising a lever pivotally mounted on the slide having one end provided with a slot and having the feed point mounted on its other end, means for moving said lever about its pivot to force the feed point into 95 the work comprising a cam actuated lever and an elongated pin projecting laterally from one end of the cam actuated lever engaging said slot in said lever carrying the feed point, and means to actuate the slide 100 to feed the work.

10. A sewing machine having, in combination, stitch forming devices including a hooked needle, a looper, a thread finger, means acting automatically upon stopping 105 the machine to sever and hold the thread, and actuating mechanism for the thread finger acting to position the thread finger close to the thread leading to said thread severing and holding means upon stopping the 110 machine.

11. A sewing machine having, in combination, stitch forming devices including a hooked needle, a looper, a thread finger, means acting automatically upon stopping 115 the machine to sever and hold the thread and to give up thread to the thread finger upon starting the machine, and actuating mechanism for the thread finger acting to position the thread finger in close proximity 120 to the thread leading to said thread severing and holding means upon stopping the machine to insure that the thread finger will properly engage the thread at the start of the next cycle of operations of the machine.

12. A sewing machine having, in combination, stitch forming devices including a hooked needle, a looper, a thread finger hav-

6
ing an upwardly curved thread engaging end, and means acting automatically upon stopping the machine to sever and hold the thread, and actuating mechanism for the thread finger acting to position the thread finger with said curved end close to the thread leading to said thread severing and holding means upon stopping the machine.

13. An inseam shoe sewing machine having, in combination, devices for guiding a lasted shoe, stitch forming devices including a curved hook needle, a feed point, and actuating mechanism for the feed point including means operated on stopping the machine to move the feed point out of engagement with the work, and operated on starting the machine to allow the feed point to engage the work.

14. An inseam shoe sewing machine having, in combination, devices for guiding a lasted shoe, stitch forming devices including a curved hook needle, a feed point arranged to engage the top of the between substance of the shoe sole, and actuating mechanism for the feed point including means operated on stopping the machine to move the feed point out of engagement with the work.

15. An inseam shoe sewing machine having, in combination, devices for guiding a lasted shoe, stitch forming devices including a curved hook needle, a feed point and actuating mechanism for the feed point including a control rod operated on stopping the machine to move the feed point out of engagement with the work.

16. An inseam shoe sewing machine having, in combination, devices for guiding a lasted shoe, stitch forming devices includ-

ing a curved hook needle, a feed point, actuated mechanism for the feed point including a control rod operated on stopping the machine to move the feed point out of engagement with the work, and operated upon starting the machine to allow the feed point to engage the work.

17. An inseam shoe sewing machine having, in combination, stitch forming devices, a channel guide fixed in the direction of feed, a feed point arranged to engage the top of the between substance of the shoe sole, and means for moving the feed point in the direction of feed across the end of the channel guide.

18. An inseam shoe sewing machine having, in combination, stitch forming devices, a channel guide fixed in the direction of feed, a feed point arranged to engage the top of the between substance of the shoe sole substantially in the plane of the root of the channel, means for moving the feed point in the direction of feed across the end the channel guide, and means for retracting the channel guide slightly preliminary to the feeding movement of the feed point.

19. An inseam shoe sewing machine having, in combination, stitch forming devices, a channel guide fixed in the direction of feed, a feed point arranged to engage the top of the between substance of the shoe sole, means for moving the feed point in the direction of feed across the end of the channel guide, and means for retracting the channel guide slightly preliminary to the feeding movement of the feed point.

ALFRED B. FOWLER.
